(57) **CLAIM**

The ornamental design for a table tennis paddle handle, as shown and described.

DESCRIPTION

FIG. 1 is a perspective view of a table tennis handle with side portions made of a resilient material.

FIG. 2 is a top view of the handle of FIG. 1.

FIG. 3 is a bottom view of the handle of FIG. 1.

FIG. 4 is a front view of the handle of FIG. 1. The back view is symmetric; and,

FIG. 5 is a left-side view of the handle of FIG. 1. The right-side view is symmetric.
